DRAFTING AND SPINNING MECHANISM

Elwin H. Rooney, Buttonwoods, R. I.

Application October 19, 1937, Serial No. 169,810

8 Claims. (Cl. 19—130)

My present invention relates to the drafting and spinning of textile fibers and more particularly aims to provide improved methods and apparatus for drafting and spinning cotton, whereby a given count of yarn, of a superior quality, may be produced with the employment of a less number of separate operations and machines.

In the drawings illustrating by way of example certain embodiments of the invention,

Fig. 1 is a cross section of one form of apparatus in accordance with the invention and for practising the method thereof, the machine there shown being referred to herein as a high-draft spinning frame or combined roving and spinning frame;

Fig. 2 is a diagram illustrating the path of the roving from the creel to a spindle;

Fig. 3 is an enlarged section corresponding to a lower lefthand portion of Fig. 1, illustrating the roll mechanism at one side of the machine;

Fig. 3A is a top view of a guide and the drafted fibrous ribbon between the inner and outer sets of rolls;

Fig. 4 is an approximately horizontal section showing one form of gearing for the set of drafting rolls seen at the right in Fig. 3;

Fig. 5 is an end view of another apparatus embodying the invention, wherein a high draft spinning frame such as that of Fig. 1 operates with sliver supplied from cans; and

Fig. 6 is a diagram illustrating the path of the sliver from the cans to a spindle in the machine of Fig. 5.

Referring first to Figs. 1 to 4 inclusive I have there shown apparatus for the practice of my method in accordance with which roving such as ordinarily prepared on slubbing frames, and which ordinarily is then further drafted in roving or fine frames or in intermediate frames, or in both intermediate and roving frames, is drafted and spun onto the spindles in a single operation carried out in the one organized mechanism. In other words, in the practice of my invention I supply to the frame on which the spinning is done roving of a coarseness such as usually produced on a slubber, or even a sliver from a drawing frame, and obtain for example 60's yarn in a single operation from 1.5 hank roving, 20's yarn from 1.0 hank roving, or from a sliver, or any other desired yarn count, starting from the roving at the corresponding slubber stage of the ordinary practice, or in some cases taking sliver direct from the drawing frame, thus dispensing entirely with intermediate and roving frames,

and, in the cases last referred to, eliminating even the slubbing frame.

The apparatus as illustrated in Fig. 1 has a similar general arrangement as the usual double-sided ring spinning frame. The main frame at 1 one end of the machine is indicated at 1. Rows of spindles 2 extend along the opposite sides of the machine, these being driven in the known manner as by a cylinder and spindle bands or tapes 3. The spindles receive yarn Y fed from an outer set of drafting rolls on a stand 4 supported on a rail 5 in a generally similar manner as in the usual spinning frame. This outer set of rolls comprises driven front, middle and back lower rolls 6, 7 and 8 and corresponding upper rolls 6', 10 7' and 8' paired with the respective lower rolls. These outer rolls, which may be of any preferred construction, are coordinated with other drafting means, to be described, in such manner that they effect but a relatively low draft, for example, drafts in the range of about 5 or 6 to about 10 or 12, as contrasted with the relatively higher drafts now generally used in spinning frames, at the expense of yarn quality, in order to satisfy present day requirements of speed and volume.

Inwardly or in back of this outer drafting roll set, in position to deliver drafted roving to the latter, I provide an initial or inner set of drafting rolls comprising in the illustrated example 30 three pairs of upper and lower rolls. These include front, middle and back pairs, the lower or driven rolls being numbered 10, 11 and 12 respectively in the drawings and the corresponding upper rolls 10', 11' and 12'. 35

As an important feature of the invention, one of these upper rolls behind the front one, the upper back roll as illustrated, is of the multiple-point construction disclosed and claimed in the United States patents to T. P. Rooney No. 1,933,222 and 2,023,032, dated October 31, 1933, and December 3, 1935, respectively. By reason of the high degree of fiber parallelizing obtainable with said pointed rolls they are peculiarly suited to the purposes of my present invention and cooperate 45 in a special manner in the novel combination disclosed. Rotary brush clearer means 13, not necessary to describe here in further detail, may be provided in association with the pointed rolls, as disclosed and claimed in a copending application 50 of Nelson A. Batchelder.

Said inner or initial set of drafting rolls are rotatably supported by a stand 14 on a platform 15, the front rolls of the inner set standing adjacent the back rolls of the outer set. The drafted 55

roving is conducted from one roll set to the other by a supporting guide 16, see Fig. 3, having a forwardly tapering guide channel 17 adapted to deliver to the bight of the back rolls of the outer set 5 a collected plurality of drafted rovings coming from the inner set, thus giving a doubling action to be referred to. Said guide is supported in operative position between the two roll sets as by a bracket 18 on one of the roll stands.

10 The inner set of drafting rolls 10, 11 and 12 is operatively arranged to afford a relatively high draft, in the range of say 15 to 20 draft in the instance of producing 60's yarns from 1.5 hank roving. They are driven in timed coordination 15 with the front set to produce the total desired draft. And in view of the high drafts accomplished by the inner roll set they may be operated at extraordinarily low speeds as compared with current standard practice on intermediate and 20 roving or fine frames.

One convenient drive is that illustrated, wherein in the inner set is actuated directly from the outer set, thereby insuring the positive coordination of the two. Referring particularly to Fig. 3, the 25 outer roll sets at the two sides of the machine may be operated by gearing such as is usual in spinning frames, including the large intermediate gears 20, (Fig. 1) one for each side. Said gears are driven by the twist gear 21 engaged with the 30 jack gear 22, the latter meshing with a gear 23 on the main drive shaft 24.

Referring again to Fig. 3, representing the rolls at the left side of the frame as viewed in Fig. 1, (those at the other side being similar and similarly driven) the corresponding large gear 20 drives the front roll twist gear 30 on the shaft of the lower front roll 8. The front roll draft gear 31 on the same shaft serves to drive the crown gear 32 on a shaft with the change gear 33 which in turn 40 meshes with the large back roll gear 34 on the shaft of the lower back roll 8. The lower middle roll 7 is driven by means of a gear 35 on the shaft of the lower back roll 8 meshing with the broad middle-roll intermediate gear 36, the latter 45 in turn drivingly engaging the middle roll gear 37. The described gearing generally is at one end of the frame, herein the head end, and that for the inner roll sets, now to be described, is at the other end.

50 The inner sets of rolls are driven from the outer sets by suitable gearing, herein located at the foot end of the frame. The shaft of the lower back roll 8 of each outer set accordingly is provided with a connecting gear 48 which meshes 55 with an intermediate drive gear 41. The general arrangement and manner of mounting of the gearing for said inner roll sets will be apparent from a consideration of Figs. 3 and 4. In this connection it will be understood that the various 60 gears aside from those on the roll shafts themselves are supported on stud shafts carried by the end frame 1 or by brackets on the latter or on the platform 15, one such main bracket being indicated at 1^a in Fig. 4. Shaft bearings are seen in 65 section adjacent the gears.

In each of the inner roll sets, the intermediate drive gear 41 above mentioned directly engages the front roll gear 42 fixed on the shaft of the lower front roll 10, thereby driving the latter. 70 The middle roll 11 is operated by a gear 43 on the shaft of the front roll 10 meshing with a change gear 44. On the same shaft with the latter is smaller gear 45 having driving engagement with a gear 46 on the shaft of said middle roll 11. The 75 drive for the back roll 12, with which the multi-

ple-pointed upper roll 12' cooperates, is by means of a further gear 48 on the shaft of the front roll 10 having driving engagement with a crown gear 49 on the same shaft with a change gear 50. The latter in turn meshes with the relatively large 5 back roll gear 51, on the shaft of said back roll 12. The number of teeth and the pitch of various gears is such as to give the desired draft by this inner set of rolls, such as drafts in the range of 15 to 20 in the example previously mentioned, 10 wherein 60's yarns are to be produced from a 1.5 hank roving.

This inner roll set, having the multiple-pointed roll 12' in combination therein, serves to reduce or transform the supplied roving to a flattened 15 ribbon-like formation having an appearance as represented somewhat diagrammatically in Fig. 3A. By the action of said pointed roll in combination with the others the individual fibers or small groups of them are in effect combed into 20 alignment and evenly distributed compactly into a band or ribbon wherein any previous twist has been substantially completely removed. The resulting absence of twist and high degree of fiber parallelization in this ribbon makes it possible 25 to accomplish at the same time a high draft, without sacrifice of quality. Drafts in the range of 15 to 25 are readily obtained, and may be carried as high as 40 if so desired. This high draft in turn makes it possible substantially to 30 reduce the roll speeds, a procedure diametrically opposite to all modern tendencies, and yet to obtain adequate production volume of yarn, of equal or improved quality.

For example, in the previously mentioned case 35 of 60's yarn, the front roll 10 of the inner set may have a speed of but about 25 R. P. M. This contrasts with common present day speeds at the front roll of a roving or jack frame, for a roving of similar hank, of about 100 to 110 R. P. M. In 40 a like case the speed of the back roll 12 paired with the pointed roll 12' may be but about 5 R. P. M.

In the combination of the inner roll set in a 45 spinning frame in accordance with my invention the further important result is accomplished of reducing the draft required of the outer set, for the production of any given count of yarn. Due to the high drafts obtainable from the inner set, the draft at the outer set may be correspondingly 50 reduced. For example, in the case of 60's yarn previously cited, I may employ a 16 draft at the inner set and but 10 draft at the outer set which feeds directly to the spindles. Similarly, if I use 55 a 20 draft at the inner set, which is well within their capacity, then in accordance with the invention the draft at the outer roll set is reduced to 8. The draft reduction at this point further makes for improved yarn quality.

From the foregoing it will be understood that 60 I have provided upon the one frame and in especially coordinated relation a first or inner set of rolls including at least one multiple-pointed or Rooney roll producing, permissibly at low speeds, a relatively high draft and a ribboning effect with high degree of fiber parallelization, in combination with a second set of rolls feeding to the spindles and at which the draft may be distinctly lower than is customary under present day practice for spinning frames. The resulting 65 yarn, despite the fact that my invention dispenses with intermediate and roving frames and the operations thereof, is in all respects equal or superior to the corresponding present day product of a ring spinning frame and in corresponding 70 75

volume. As indicated, important contributing factors in this result are the ribboning, fiber-paralleling and straightening effect of the inner roll set, the slow speed of the latter, particularly at 5 their back rolls, and the short draft at the outer rolls. The construction and arrangement illustrated in Figs. 1 to 4 is adapted for the production of yarns of any desired count including the finer counts, such as those above a count of about 20, 10 and I have above referred to the production of 60's yarns merely as one example.

In further combination with the described roll drafting arrangement I provide for doubling of the roving, in association with novel means affording an adequate supply of roving. The number and arrangement of the rovings, as to doubling, is indicated diagrammatically in Fig. 2, representing the inner and outer sets of rolls and the path of travel of the roving through them. 20 Four separate rovings R are supplied to the inner roll set from a creel of novel form for a spinning frame, to be referred to.

As indicated in said Fig. 2 these four rovings are conducted to the inner roll set in pairs, those 25 of each pair entering the back rolls $12, 12'$ in position closely adjacent each other, for doubling into a single element in their travel through the inner roll set. For this purpose the rovings of each of the two pairs are entered to the back 30 rolls $12, 12'$ through suitable condensing guides 12^a , Fig. 3, one for each roving pair.

From the inner roll set the rovings thus doubled are conducted as by means of the connecting guide 16 across to the back rolls $8, 8'$ of the 35 outer set. The two doubled rovings coming from the inner set are caused by the guide 16 to approach each other closely, so as to run into said back rolls of the outer set in side by side relation, for further doubling in the course of the 40 travel through the front roll set. In this manner one yarn of the desired count for each of the spindles 2 emerges from the front rolls $6, 6'$.

To accommodate the necessary roving supply I have herein illustrated in novel combination 45 with my high-draft spinning frame a multiple-deck creel, supporting the spools or bobbins 60 in the illustrated example at four different levels above the frame. The several decks may be supported one above the other as by vertical rods 61 extending upwardly from the platform 15 or other fixed part of the machine frame. For each deck of spools or bobbins I provide a guide, illustrated as a horizontal guide bar 62 . The rovings from the supplies at the opposite sides of these 55 centrally disposed guides are conducted over the latter in opposite directions and downwardly to a lower guide 63 around which they pass outwardly to the guides 12^a adjacent the back rolls $12, 12'$ of the inner sets. It will be understood 60 that half of the rovings lead outwardly to one side of the machine and the other half to the opposite side.

The four rovings to be supplied to any one set of rolls along the machine may be taken from 65 any convenient four spools or bobbins in the adjacent portion of the creel above that particular roll set. One arrangement which I have found convenient and which makes it easy for the operator to follow and attend to the roving supply is that indicated in Fig. 1. In this 70 case the four rovings for the particular roll set are taken one from each deck of the creel and from bobbins or spools standing in substantially the same vertical plane, it being understood that 75 the various supply packages, whether in the form

of bobbins, spools or otherwise, may be disposed in staggered relation, both as to supplies at any one level and as between the succeeding levels or decks. The package supplies, which in the case of the production of 60's yarns for example 5 would consist of 1.5 hank roving, may be larger than heretofore used in a spinning frame, 10-inch bobbins, for example, being employed instead of 6 or 8 inch. Thus the supply is adequate for many hours, frequently for from two to three 10 mill weeks without replenishment or attention by the operative.

It will thus be seen that in accordance with my drafting and spinning method and apparatus various intermediate steps or processes are eliminated, with corresponding reduction in equipment and operating costs. All this is accomplished without sacrifice in the quality of the 15 yarn but to the contrary with a resulting improved product more comparable to the high- 20 grade yarns of half a century ago, before quality began to be sacrificed for speed and volume. At the same time the volume of production per working period is but little if any reduced from that considered necessary under present day conditions. 25

Assume again a specific case, say the production of a 60's yarn as previously used as an example. In accordance with my method and with my apparatus as disclosed and described in connection with Figs. 1 to 4, I may start at my spinning frame with a 1.5 hank roving, for instance, said roving being the product of a slubbing frame. This roving is doubled and drafted 16 through the medium of the inner roll set, giving 35 12 hank. It is then doubled and drafted 10, in the operation of the front roll set, giving 60 hank, that is, 60's yarn. Or I may employ drafts of 20 and 8 at said two stations of my spinning frame, or other draft settings proportioned to 40 afford the desired count starting with a given roving product of a slubber.

In contrast with the process last described the general procedure with regular or standard equipment has been substantially as follows: Starting 45 at a corresponding point in the yarn production, namely with the product of a slubbing frame, such usual method would take say 1.11 hank roving which is doubled and drafted 6 in an intermediate frame, giving 3.33 hank. This latter is taken from the intermediate frame and installed in a fine or roving frame, where it is doubled and drafted 6, giving 10 hank. The latter in turn is taken from the fine frame and 55 installed in a spinning frame where after doubling it is drafted 12, giving 60's yarn.

In accordance with another practice, under what is known as the Casablanca high-draft method, the procedure for the production of 60's 60 yarns would be the following. Starting with the product of a slubbing frame, roving of say 2.0 hank is doubled and drafted 6, this draft being performed in a fine or roving frame, giving 6 hank. From this fine frame the 6 hank material 65 is installed in a spinning frame and on doubling is given a 20 draft, resulting in 60's yarns.

Thus it will be seen that in accordance with my present method and the apparatus of my invention I perform in a single process and by 70 the use of a single organized apparatus a result which requires three distinct operations, in three separate machines, under the regular procedure and which under the Casablanca method requires at least two separate and distinct opera- 75

tions, in two different machines. Moreover, my resulting product is of superior quality.

Referring now to Figs. 5 and 6 I have there illustrated another form of apparatus in accordance with the principles of my invention, more particularly adapted for the production of the coarser counts of yarns, say up to and including 20's. In this instance the invention contemplates going directly from a drawing frame, taking the sliver products of the latter, and in one operation producing therefrom spun yarn Y.

Referring to said Fig. 5 I have there indicated at 1 a high-draft spinning frame which in all respects not otherwise mentioned may be the same as that above fully described in connection with Figs. 1 to 4. The sliver S as generally produced on a drawing frame is coiled in cans 10. In the interests of compactness and with a view to conserving floor space and to enable the installation of a greater number of units in a given area, the cans 10 in accordance with the invention are disposed at a level above the spinning frame 1, as upon a platform 11 overlying substantially the entire frame. The platform is of substantial construction adequate to hold the large number of cans and also to allow an operative to move about on the platform to tend the cans. The provision of overhead cans and associated feeding means, broadly, for use with drafting frames of various types, is the invention of Nelson A. Batchelder and is disclosed and claimed by him in a copending application.

In the form illustrated in Fig. 5 the platform 35 is mounted on pillars 12 extended upwardly from the floor on which the spinning frame 1 stands, any desired number of such pillars being distributed along the frame at its opposite sides. Additional cross ties 13 may be provided at the 40 frame ends and elsewhere as necessary.

The slivers from the various cans are conducted upwardly through suitable guides 14 which may be supported on a frame structure rising from the platform 11 at the ends thereof 45 and at suitable intermediate points. As illustrated said supporting structure includes, for each side of the machine, and at the several points referred to, an upright post 15 carrying supporting arms 16, 17.

From the guides 14 the slivers pass around one or more guide and feed rolls, of which three are shown in the present instance, numbered 18, 19 and 20. These rolls are journaled on the supporting frames previously mentioned and are 55 driven one from the other as by the corresponding gears 18', 19' and 20'. From the roll 20 the last of the series, the slivers are conducted downwardly, through suitable guide formations in the platform 11, to lower guide rolls 21, 22 having 60 bearings on a fixed part of the spinning frame 1. The slivers as shown pass downwardly around the first of said lower guide rolls and upwardly over the adjacent one, leading from the latter to the back rolls 12, 12' of the inner set. The top 65 roll 12' of this back pair, as in the previous instance, is such as described in the Rooney patents mentioned, having a drafting formation comprising a multiplicity of outwardly projecting points.

Suitable means is provided for actuating the lower guide rolls 21, 22 and the corresponding upper guide rolls 18, 19 and 20 in timed relation with the drafting rolls to which the sliver is presented. For this purpose I have herein represented the one lower roll 22 as driven by a short

chain 23 on a sprocket on the shaft of the lower back roll 12 or otherwise driven positively and directly from the latter. The two lower guide rolls 21 and 22 are in turn drivingly connected as by a chain 24 extending around gears or sprockets on the roll shafts. For driving the upper rolls 18, 19, 20 in similar timed relation a drive chain 25 is extended upwardly to actuate a change gear 26 rotatably supported on the platform 11 or on one of the cross pieces 13. Said chain 25 at its lower end passes around a gear or sprocket on the shaft of the lower back roll 12 or is otherwise directly driven from the latter. The change gear 26 drives a further gear 27 on a shaft with a sprocket 28, these parts also being operatively supported on the platform or cross members. The sprocket 28 in turn drives a chain 29 extending upwardly about a sprocket on the shaft of the inner roll 20 of the upper set. The several feed and guide rolls, including both the lower and the upper sets, are in this manner positively coordinated and driven in timed relation to the drafting rolls of the spinning frame, assuring a continuous steady feed of the sliver from the cans to the back rolls 12, 12' of the inner set of drafting rolls.

In Fig. 6 I have represented diagrammatically the path of two slivers S from their cans 10 and through the drafting rolls of the two sets for spinning a single yarn onto the corresponding 30 spindle 2. It will be noted that for each spindle two slivers S, from a corresponding number of cans, are fed to and drafted in the inner set of drafting rolls 18, 18', 19, 19', and 20, 20', each emerging singly from the front rolls 18, 18' of 35 this set. From the latter these drafted slivers are guided across to the front drafting roll set in such manner as to enter the back pair 8, 8' in side-by-side relation for doubling into a single element or yarn in the operation of said outer 40 roll set.

As one example of a drafting and spinning operation in accordance with the method and apparatus of Figs. 5 and 6 I may employ, for each spindle, two single 40-grain or .2 hank sliver 45 supplied in cans from a drawing frame. Said single slivers are individually given a draft of 20 in the inner roll set, forming 4.0 hank. Two of the latter units are then doubled and drafted 50 through the operation of the outer set of 50 drafting rolls, giving 20's yarn. It will be understood that the particular drafts here cited are examples only. In general, however, and as in the preceding figures, the inner set of rolls serve to afford a relatively high draft and accurate 55 paralleling of the fibers, at low roll speeds, while the outer set affords a comparatively lower draft.

It will be understood that my invention, either as to means or method, is not limited to the exemplary embodiments or steps herein illustrated or described, and I set forth its scope in my following claims.

I claim:

1. A combined roving and spinning frame for drafting and spinning textile fibers, comprising, in combination, a frame supporting a series of yarn spindles, an outer roll stand provided with upper and lower drafting rolls disposed in front, intermediate and back pairs, said rolls feeding to the spindles, a second roll stand feeding to the first and equipped with a plurality of pairs of drafting rolls, each pair including upper and lower rolls, and the upper roll of at least one pair behind the front pair having a drafting formation comprising a multiplicity of outwardly pro- 70

- jecting points, supporting means on the frame for a roving supply comprising at least four roving packages per spindle, guide means for directing four rovings from the supplies, for each spindle, and introducing them in pairs to the rolls of the rear stand for doubling and high drafting thereby, forwardly convergent guide means between the two stands for conducting the two resulting drafted rovings to the rolls of the front stand for further doubling and drafting thereby into a single unit for presentation to the corresponding spindle, means to drive the rolls of the outer stand to effect a selected relatively low draft, and drive connections between the rolls of the outer stand and those of the inner stand to drive the latter to afford a relatively high draft but at low speeds of the rolls as compared with that customary for roving frames.
2. A combined drafting and spinning apparatus, comprising, in combination, a frame, a plurality of spindles thereon, an outer set of drafting rolls on the frame including front, intermediate and back pairs of upper and lower rolls, an inner set of drafting rolls on said frame and also including front, intermediate and back pairs of upper and lower rolls, the upper roll of at least one pair of said inner set having a drafting formation composed of a multiplicity of substantially radial wire-like points, guiding means to conduct the material being drafted from the inner roll set to the outer set, drive means on the frame to drive the shaft of the lower front roll of the outer set, gearing having driven connection with said front roll shaft and including change gears for driving the intermediate and the back rolls of said outer set, said gearing operatively disposed at a given end of the frame, gearing connections between a driven element of the outer set and the lower front roll shaft of the inner set, and interconnecting gearing including change gears drivingly associating the intermediate and back rolls of the inner set with the front roll shaft thereof and mounted on the frame at a location spaced lengthwise the frame from the gearing for the outer roll set.
3. A combined drafting and spinning apparatus, comprising, in combination, a frame, a plurality of spindles thereon, an outer set of drafting rolls on the frame including front, intermediate and back pairs of upper and lower rolls, an inner set of drafting rolls on said frame and also including front, intermediate and back pairs of upper and lower rolls, the upper roll of at least one pair of said inner set having a drafting formation composed of a multiplicity of substantially radial wire-like points, means to drive the outer roll set to afford a selected relatively low draft of not more than about 10, and gearing connections between the outer set and the inner roll set to operate the latter at low roll speeds but in such interrelation of the rolls thereof as to afford a high draft in the range of from about 15 up to about 40.
4. A combined drafting and spinning apparatus, comprising, in combination, a frame, a plurality of spindles thereon, an outer set of drafting rolls on the frame including front, intermediate and back pairs of upper and lower rolls, an inner set of drafting rolls on said frame and also including front, intermediate and back pairs of upper and lower rolls, the upper roll of at least one pair of said inner set having a drafting formation composed of a multiplicity of substantially radial wire-like points, guiding means to conduct the material being drafted from the inner roll set to the outer set, means to drive the outer roll set to afford a selected relatively low draft of not more than about 10, and gearing connections between the outer set and the inner roll set to operate the latter at low roll speeds but in such interrelation of the rolls thereof as to afford a high draft in the range of from about 15 up to about 40.
5. A combined drafting and spinning apparatus, comprising, in combination, a frame, a plurality of spindles thereon, an outer set of drafting rolls on the frame including front, intermediate and back pairs of upper and lower rolls, an inner set of drafting rolls on said frame and also including front, intermediate and back pairs of upper and lower rolls, the upper roll of at least one pair of said inner set having a drafting formation composed of a multiplicity of substantially radial wire-like points, roll drive gearing for said sets of rolls to afford a high draft at the inner set and a relatively low draft at the outer set, supporting means on the frame for a plurality of at least four material supplies for each spindle, and guide means for conducting the material for each spindle to cause doubling thereof at the inner roll set and a further doubling into a single unit at the outer roll set, for passage to the respective spindle.
6. A combined drafting and spinning apparatus, comprising in combination, a frame, an initial or inner set of rolls thereon including at least three pairs disposed as front, intermediate and back pairs, a second or outer roll set of at least three roll pairs including front, intermediate and back pairs, a drive shaft on the frame, gearing connections between the drive shaft and the shaft of the lower front rolls of the outer set, gearing means to drive the intermediate and the back roll shafts of said outer set from said front roll shaft to afford drafts at said outer set of a relatively low order not more than about 10, said gearing located at one end of the frame, gear means connecting a roll shaft of said outer set with the lower front roll shaft of the inner set, and operatively interconnecting gearing for the other lower roll shafts of said inner set, said gearing mounted at the other end of the frame and including connections between the lower front roll shaft of said inner set and both the lower intermediate and the lower back roll shafts thereof and of a ratio to afford a relatively high order to draft at said initial or inner roll set, of a minimum substantially exceeding the draft at the outer roll set and up to about 25 to 40, but at low speeds of the rolls as compared with those customary for high drafting.
7. Apparatus for drafting and spinning textile fibers according to claim 3 wherein there is provided for the material to be drafted a material supply platform mounted to overlie the frame, said platform dimensioned and arranged to accommodate material supply cans, one for each initial material unit, the guide means for the material including feeding and guiding rolls, some of said rolls being rotatably mounted above the platform and adjacent the supply cans and others rotatably supported adjacent the initial rolls of the inner set to deliver the material units thereto, and positive non-slip gearing means for drivingly connecting and synchronizing said initial rolls and all of said feeding and guiding rolls.
8. That novel process of drafting and spinning textile fibres into yarn on a ring frame which comprises effecting a complete drafting and

spinning from an initial fibre supply of at least ordinary roving coarseness, in a one-frame or single operation as contrasted with separate operations on two or more successive frames such as intermediate, fine and spinning frames successively or intermediate frames and spinning frames in successive separate operations, said process further comprising the steps, for each spindle, of supporting in condition to be drawn upon a plurality of individual supplies of lengths of said fibrous textile material to be drafted, conducting the lengths from the supplies and first drafting them with a high draft substantially exceeding a draft of about 10 but at a relatively slow speed of the drafting instrumentalities as compared with that customary for like drafts and materials, and effecting said drafting in a manner to comb and highly parallelize the fibres of each supply length into thin flat ribbon form wherein the individual fibres are straightened and substantially free of twist,

immediately thereafter and as part of the same single continuous one-frame operation further drafting and simultaneously combining into a unit at least two adjacent drafted ribbons for each spindle by a selected relatively low draft of not more than about 10 while operatively correlating the instrumental speeds at the initial relatively high drafting stage and at said further relatively low drafting stage to afford the desired total draft corresponding to the usual total of the two or more ordinarily separate drafting operations hereby replaced and at the same time avoiding at any stage the concurrence of both a high draft and a high instrumental speed, thereby materially to improve the quality of the resulting product yet substantially maintaining the production volume per time unit, and finally in the same one-frame operation spinning the resulting drafted unit onto a spindle to form yarn thereon.
